UNITED STATES PATENT OFFICE

2,536,142

DRAFTING MACHINE

Morris Sanders and Joseph L. Sanders,
Rochelle Park, N. J.

Application January 24, 1950, Serial No. 140,212

2 Claims. (Cl. 33—79)

1

This invention relates generally to parallel motion drafting devices of the kind in which the several tools which the draftsman handles most frequently are embodied, in principle, in one unit to obviate the necessity of a draftsman reaching about for a required tool and thereby enabling the draftsman to keep his attention concentrated directly upon the drawing.

Drafting devices of this character are common in which adjacent ends of two arms are pivoted together, the free end of one arm being secured to the remote side of a drafting board while the free end of the other arm is provided with a head comprising a protractor and straight edges which are in fixed angular relation and move about the center of the protractor as an axis.

Hitherto the arrangement of drafting machines of the endless band and pulley type, to which this invention particularly relates, has been such that the protractor is situated under the arms containing the endless band, making it difficult to observe the markings on the protractor when the machine is to be set at certain angles; or in machines having the protractor above the arms, the mechanical arrangement for setting these machines automatically to certain prescribed angles must be actuated from a single particular point.

One object of this invention is to provide an arrangement whereby the protractor is visible in all positions of the arm, and yet having means for the automatic setting of the machine to certain prescribed angles arranged so that it may be actuated without the necessity for the operator to move his hand or to change the position of his hand.

Another object of this invention is to provide means for disengaging the automatic indexing mechanism, so as to enable the operator to set the arms in any position and lock the arms in that position.

Another object of this invention is to provide means so that the operator need not observe the protractor while setting the machine to certain prescribed angles, but may arrive at a desired angle through audible means.

Another object of this invention is to provide means for compensating for the deflection of the arms at the elbow by boring the bearing seat in the arm of the anchor at the necessary angle from the vertical, so that the deflection automatically is compensated for equally in all positions of the arms.

Another important object of this invention is to provide means for parking the machine when not in use, so that the entire surface of the draw-

2

ing board is free and clear, and yet retaining the parallel positions of the arms, even on an inclined board.

With the foregoing and other objects in view which will appear as the description proceeds, the invention consists of certain novel details of construction and combinations of parts herein-after more fully described and pointed out in the claims, it being understood that changes may be made in the construction and arrangement of parts without departing from the spirit of the invention as claimed.

In the accompanying drawing a preferred form of the invention has been shown.

15 In said drawing:

Figure 1 is a top plan view of the entire machine in parking position;

Figure 2 is an enlarged, fractional top view and sectional view on the line 2—2 of Figure 3 of 20 the head assembly;

Figure 3 is a sectional view of the head assembly on the line 3—3 of Figure 2;

Figure 4 is an enlarged fractional view of the head assembly;

25 Figure 5 is an enlarged fractional sectional view, as the sectional portion of Figure 2, but showing some of the parts in positions which differ from their positions shown in Figure 2; and,

30 Figure 6 is a fractional sectional view on the line 6—6 of Figure 2.

Similar reference characters refer to similar parts throughout the several views.

Referring first to Figure 1, the drafting machine 35 includes four housings 1 held apart by the tubes 2 through which the endless bands 3 pass. One such housing is mounted pivotally at the anchor which consists of a bracket 4 affixed to the drawing board 5 by any suitable, well known means.

40 Referring to Figures 2 to 5, the head consists of a housing 1 into which a needle bearing 7 (Figure 3) has been pressed. A tubular shaft 29 rotates freely in the bearing 7 and is affixed securely to a casting 30, which preferably is made

45 as a unit with a combination protractor head 31 and a pulley portion 32. A belt or an endless band 3 passes round the pulley portion 32. Rotating freely inside the tubular shaft 29 is a shaft 33, the upper portion of which is securely affixed in

50 the hub of a vernier plate 34. This vernier plate 34 fits into the annular bore of the protractor head 31 and is rotatable therein. To the lower portion of the shaft 33 is affixed a rule holder plate 42, which preferably is formed as a unit

55 with a parking tongue section 59.

A ring-shaped notched plate 35 is affixed to the lower periphery of the vernier plate 34 by means of the screws 36. An actuating circular notched plate or disk 37 is interposed between the protractor head 31 and the vernier plate 34, and the shaft 33 is extended through the center of the plate 37.

A knurled ring 38 of plastic material or the like rests upon, and is angularly movable, on the top of the vernier plate 34. Two shouldered pins 39 are securely attached to the actuating notched plate 37 fit freely through enlarged holes 40 in the vernier plate 34 and are secured to the knurled ring 38. A knob 41 of plastic material or the like is securely affixed to the hub of the vernier plate 34.

A rocker arm 43 is pivotally secured to the protractor head 31 at 44. A pin 45 connects the rocker arm 43 to a cross-slide 46. At the upper portion of this pin is a roller 47 which engages the notches of the actuating notched plate 37. The outer extremity of the cross-slide 46 is connected, by means of pivot pin 48, to a pawl 49 which engages the notches of the notched plate 35. The pawl 49 is pivotally secured to the inner side of the member 31 by means of a bolt 50 or the like. Beyond the bolt 50, the pawl 49 is bent right angularly, and its thus bent portion is extended through an open, radial slot 51 in the peripheral portion of the member 31 (Figure 6). The end portion 49a of the pawl 49 at the outer side of the member 31 is parallel to the latter and adapted to be engaged by the cam portion 52 of a thumb lock member 53. The latter is secured to one end of a bolt 54, whose center portion is rotatably extended through the member 31, and whose other end is threaded into a clamp member 55, which is located at the inner side of the member 31. The clamp member 55 has a reduced portion, which is interposed between the parts 35 and 34 (Figure 3), for the purpose of preventing an axial movement of the notched plate 35.

If the lock member 53 is in the position shown in Figures 2 and 3, the pawl 49 is forced toward the periphery of, and into the notches of, the member 35 by means of a spring 56 which lies in a recessed portion of the protractor head 31, and one end of the spring 56 is affixed to the inside of the protractor head at 57 (Figure 2). The other end of the spring 56 is affixed to the extremity of rocker arm 43 at 58.

The parking tongue section 59 of the ruler holder 42 is provided with a perforation 60 (Figures 1, 2 and 4), adapted to have extended thereto a pin 61 which is secured to the anchor bracket 4, in order to retain the device in its parking position.

The operations of our new and improved automatic indexing mechanism, whose construction is described above, are carried out as follows:

To set the straight edges at any one of the prescribed angles, the pawl 49 is disengaged from the notched plate 35 in the following manner:

A slight rotation of the knurled ring 38 causes the actuating notched plate 37 to rotate by means of the pins 39. This rotation pushes the roller 47 and the shaft 48 outwardly toward the periphery of the member 31. The rocker arm 43 rotates in a counter-clockwise direction and the cross-slide 46 moves to the right. This forces the pawl 49 to move in a clockwise direction around the bolt 50, thus freeing itself from the notched plate 35. A further rotation of the ring 38 will move the shouldered pins 39 against the

side of the holes 40 in the vernier plate 34, and the vernier plate will turn with any additional motion.

When the actuating notched plate 37 is rotated so that the roller 47 passes into the next notch, a slight click is audible, and a slight additional pressure is necessary to turn the vernier plate 34 further. This occurs every fifteen degrees.

When the ring 38 is released, the tension of the spring 56 will force the roller 47 into the notch in the actuating notched plate 37, and the pawl 49 will move through the reverse of the aforementioned action into a notch in the notched plate 35.

To set straight edges at an intermediate angle, a slight rotation of the thumb lock member 53 causes the pawl 49 to move around the bolt 50 in a clockwise direction, freeing the notched plate 35 as may be seen in Figure 5. Further rotation of the thumb lock member 53 causes the clamp member 55 to bear with its non-reduced portion against the periphery of the notched plate 35, locking it securely to the protractor head 31.

Since certain changes may be made in the above article and different embodiments of the invention could be made without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the invention which as a matter of language might be said to fall therebetween.

Having thus fully described our said invention, what we claim as new and desire to secure by Letters Patent in the United States is:

1. In a drafting machine which has two pairs of housings connected to each other by tubes through which pass endless bands, in combination, an anchor bracket adapted for securing the device to a drawing board and being pivoted to the first one of said housings, the second and the third housing being pivoted to each other, and the fourth housing being constructed as a drafting machine head housing and having a needle bearing in its center, a tubular member encompassed by said needle bearing and being rotatable thereon, a protractor head having a pulley portion around which passes one of the endless bands and being secured to said tubular member, an upright shaft rotatably extended through said tubular member, a perforated vernier plate secured to the upper end of said shaft and being rotatable in said protractor head, a rule holder plate secured to the lower end of said shaft and having a parking tongue section which is provided with a perforation, a ring-shaped plate having a notched outer periphery and being secured to the lower side of said vernier plate, a peripherally notched disk through whose center said shaft is extended being interposed between said protractor head and said vernier plate, a knurled ring coaxial with said vernier plate being located upon the outer side of said vernier plate, upright pins secured to said knurled ring and extended loosely through the perforations of said vernier plate into said notched disk, a rocker arm having one of its ends pivoted to said protractor head, a cross-slide radially movable in said protractor head being pivoted to said rocker arm intermediate its ends, a roller secured to that por-

tion of said rocker arm to which said cross-slide is pivoted and being adapted for engaging the notches in the periphery of said notched disk, a pawl adapted for engaging the peripheral notches of said ring-shaped plate and being pivotally connected to said cross-slide, as well as to said protractor head, a bolt rotatably extended through said protractor head, a thumb lock lever having a cam portion adapted for engaging said pawl and being secured to one end of said bolt, a clamp plate secured to the other end of said bolt having a reduced portion which is interposed between said ring-shaped plate and said vernier plate, resilient means interposed between said protractor head and said rocker arm being adapted for forcing the latter against said notched disk, and a pin secured to said anchor bracket being adapted for extending through the perforation in the parking tongue section of said rule holder plate for the purpose of retaining the device in its parking position.

2. In a drafting machine head, in combination, a housing having a needle bearing in its center, a tubular member encompassed by said needle bearing and being rotatable thereon, a protractor head having a hub portion which is secured to said tubular member, an upright shaft rotatably extended through said tubular member, a perforated vernier plate secured to the upper end of said shaft and being rotatable in said protractor head, a ring-shaped plate having a notched

outer periphery and being secured to the lower side of said vernier plate, a peripherally notched disk through whose center said shaft is extended being interposed between said protractor head and said vernier plate, a knurled ring coaxial with the vernier plate being located upon the outer side of said vernier plate, upright pins secured to said knurled ring and extended loosely through the perforations of said vernier plate into said notched disk, a rocker arm having one of its ends pivoted to said protractor head, a cross-slide radially movable in said protractor head being pivoted to said rocker arm intermediate its ends, a roller secured to that portion of said rocker arm to which said cross-slide is pivoted, a pawl being adapted for engaging the peripheral notches of said ring-shaped plate and being pivotally connected to said cross-slide as well as to said protractor head, a bolt rotatably extended through said protractor head, a thumb lock lever having a cam portion adapted for engaging said pawl and being secured to one end of said bolt, a clamp plate secured to the other end of said bolt having a reduced portion which is interposed between said ring-shaped plate and said vernier plate, and a spring interposed between said protractor head and said rocker arm being adapted for forcing the latter against said notched disk.
